(57) **CLAIM**

The ornamental design for a display screen with transitional graphical user interface, as shown and described.

DESCRIPTION

FIG. 1 is a front view of a display screen with transitional graphical user interface showing a first image in a sequence according to claimed design;

FIG. 2 is a second image thereof; and,

FIG. 3 is a third image thereof.

The appearance of the image transitions sequentially between the images shown in FIGS. 1-3.

The process or period in which an image transitions to another image forms no part of the claimed design.

The solid black is part of the claimed design.

The broken-lines showing of the display screen in all views form no part of the claimed design. The broken line showing of the graphic element in FIGS. 1-3 and the text in FIG. 3 form no part of the claimed design.
